(57) **CLAIM**

The ornamental design for a tire tread, as shown and described.

DESCRIPTION

FIG. 1 is a perspective view of a tire tread with the tire to which it can be attached shown in dashed lines for environmental purposes.

FIG. 2 is a front view of the tire tread and environmental tire of FIG. 1;

FIG. 3 is a right side view of the tire tread and environmental tire of FIG. 1, it being understood that the left side view is a mirror image;

FIG. 4 is a section view taken along line 4 of FIG. 2; and, FIG. 5 is an enlarged view of the tread of FIG. 2.

The dashed lines in the drawings show environmental features of the tire and form no part of the following claim.

1 Claim, 5 Drawing Sheets

FIG. 1

FIG. 2

FIG. 3

FIG. 4

FIG. 5
